D10-9. OR D 818 EX

Des. 818

J. and R. Shepherd of New York, N.Y.
Letters Patent No. 818, dated July 29, 1856.

The schedule referred to in these Letters Patent and making part of the same,

To all whom it may concern;

Be it known that we, J. and R. Shepherd, of the City County and state of New York, have invented or produced a new Ornamental Design for Clock fronts, and we do hereby declare that the following is a full, clear and exact description of the same, reference being had to the accompanying drawings, forming part of this specification, in which.

Fig. 1, is a face view of a clock case front, showing our design.

Fig. 2, is an inverted horizontal profile of the same.

Similar letters of reference in each of the two figs, indicate corresponding parts.

A, is the circular opening which exposes the dial, and B, the opening which exposes the pendulum.

C, is a raised scroll ornament directly under the opening B, and forming a part of the base D, of the case front.

E, F, are two other raised scroll ornaments, the lower or rolled part of which resting on or just above the opening B, and the other portion making a sweep outward and inward on either side of the case front, and extending up above the top of the dial opening and terminating in ornamental

device a, b, and joining with tendrils F,F which strike out from a large leaf ornament C of the form of a bulb or cup at the top of the case front. The main stem C, of each of the tendrils, is ornamented with a small leaf bulb or cup d, and blossoms e, and the minor stems f,f, have each a blossom g, of the character shown. Between the tendrils F,F and striking up from the centre of the ornament C, is a tendril H, the stems h,h,h, of which have each a blossom i, as represented. And behind the tendrils F,F are leaf ornaments j,j, which strike out from the leaf bulb or cup C. —

I,I, are raised ornaments or tendrils striking out from the lower part of the scrolls E,E, and terminating at the corners of the base D, as represented.

K, is a vine, with fruit L, and leaves m, disposed as shown, arranged round the lower half of the case front as represented. —

The vine and the ornaments before described form a wreath which serves as a border or edging to the whole of the clock case front, as shown. —

What we claim as our invention and desire to secure by Letters Patent, is

The combination and arrangement, as described, of the several ornaments specified and shown, for the purpose of forming a new and ornamental design for a clock case front.
